UNITED STATES PATENT OFFICE.

DAVID B. KERR, OF PHILADELPHIA, PENNSYLVANIA.

DESIGN FOR UPHOLSTERY FABRIC.

SPECIFICATION forming part of Design No. 17,799, dated October 18, 1887.

Application filed September 14, 1887. Serial No. 249,726. Term of patent 3½ years.

To all whom it may concern:

Be it known that I, DAVID B. KERR, a citizen of the United States, residing at Philadelphia, in the county of Philadelphia and State of Pennsylvania, have invented and produced a new and original Design for an Upholstery Fabric; and I do hereby declare that the photographic print accompanying this specification conveys to any one skilled in the art a clear understanding of the same, and is sufficient to enable such person to use my invention.

The leading features of my design consist in the representation of flowers marked A, that resemble wild roses, and at B flowers that resemble tulips. The rest of the design is made up of leaves and flowers, as shown in the photographic print making a part of this specification.

What I claim as my invention is—

The design for an upholstery fabric, consisting of wild roses A A and tulips B B, with flowers and leaves, as shown in the photographic print.

DAVID B. KERR.
